INVENTOR.

Abraham S. Pinkus,

BY

M. H. Langridge

ATTORNEY.

UNITED STATES PATENT OFFICE.

ABRAHAM S. PINKUS, OF NEW YORK, N. Y.

ADJUSTABLE WRENCH.

Application filed March 7, 1927. Serial No. 173,516.

This invention relates to adjustable wrenches and has for an object to provide wrenches of this character which are automatic in operation, which are simple to construct and easy to operate. The invention more particularly resides in the construction of a novel type of handle, in the sliding engagement of the jaws and in the construction of the slot by which the jaws are adjustable.

These objects will be more fully understood from the following specification and the accompanying drawings in which, Fig. 1 is a general view of a wrench constructed according to my invention, Fig. 2 is a cross-section of the handle on line 2—2 in Fig. 1; Fig. 3 is a side view of the so-called fixed jaw of the wrench and Fig. 4 is a corresponding end view. Fig. 5 is a side view of the sliding jaw and Fig. 6 is an end view of the sliding jaw. Fig. 7 shows a method of forming the jaw from a single forging and Fig. 8 is an assembly of Fig. 7.

The present invention is applied to wrenches constructed on the toggle principle. That is, the jaws are constructed to slide upon each other and are pivoted by a toggle action to the handle where a preliminary movement of the handle brings the jaws together to bear upon the nut which is thereafter turned by the wrench handle, and a movement of the handle in the opposite direction releases the jaws so that the operation of the wrench is the equivalent of a ratchet action. This principle is understood to be old and well established in the art of wrench manufacture.

The handle of this wrench is formed from a pair of plates the edges of which are formed in a semi-circle and the centre depressed so that when these plates are brought together and welded along their edges, they form a cylindrical edge with a depressed interior section and the end is rounded with the opposite end formed into a jaw to engage the wrench head. This makes a light, strong and smooth handle which is easy to grip, does not require knurling and the rounded edges prevents it from engaging other objects as the wrench is operated.

The fixed jaw is preferably made from two forgings which are shaped under a drop hammer to include the slot for the sliding jaw when these forgings are welded on their abutting faces, also an arcuate slot through which the sliding jaw is pivoted to the handle.

The sliding jaw is provided with a comparatively deep tongue to engage the slot in

the fixed jaw. A transverse slot is provided in this tongue to engage the pivot of the handle. This tongue is also undercut on its central lower edge to clear the pivot of the fixed jaw and to limit the movement of the jaw.

Referring to the drawings, 11 is the handle, 12 is the fixed jaw which is pivoted to the jaw of the handle 14 by pivot 15, and 13 is the sliding jaw which is pivoted to the jaw of the handle by pivot 16. The handle as shown in section in Fig. 2 comprises a pair of plates 11 the edges of which are semi-cylindrical as indicated at 17 and 18 while the centre is depressed. These plates are welded along their abutting edges making a handle with rounded edges and a rounded end as shown in Fig. 1. These plates are also formed into the disc shaped ends 14 which form a pair of jaws to which the wrench head is pivotally connected.

The jaw in Fig. 3 is referred to as the fixed jaw because the other jaw slides thereon but it should be noted that this jaw is pivoted in the jaws of the handle 14 by the pivot 15 through the pivot hole 22. This jaw is also preferably depressed at 21 on each side to receive the discs 14 of the handle jaw. The arcuate slot 23 is formed in the sides of this jaw to permit pivot 16 to move freely therein as the jaw 12 moves on pivot 15.

The sliding jaw 13 is provided with a tongue 26 which slides in the slot 25 of jaw 12. This tongue is provided with a central transverse slot 27 which is engaged by the pivot 16 of the handle 11 and through which the toggle action is obtained for the movement of the jaws of the wrench. It will be noted for instance, if jaw 12 is stationary and the handle moved to the right, jaw 13 will be slid towards 12 and a movement of the handle in the opposite direction will reverse this action.

It will be noted from the dotted outline of the relation of the jaw 12 to jaw 13 in Fig. 5, that the ends *a* and *b* of the tongue 26 project below the pivot 24, which is the body of the pivot 15. This is also shown in Fig. 4. The free movement of jaw 13 requires that its lower edge be undercut as at 28 to clear 24. It is apparent that the pivot 24, when in place, acts as a stop to limit the movement of the sliding jaw in the slot 25.

The fixed jaw may be made from a pair of forgings as indicated in Fig. 4 and which are welded on their abutting faces on the line

- c—d.* The seam where the weld is formed is grooved as indicated at 31 so that the corners of the slot only have to be machined to make an accurate bearing for the tongue 26.
- 5 Another method of forming the fixed jaw is shown in Figs. 7 and 8. The jaw 12 is formed from one forging split and spread apart as shown in the wings 35 and having the end projections 36 on the opposite side.
- 10 When shaped as in Fig. 7 these wings are formed as required for the sides of the jaw and then they are brought into alignment under a die to the shape shown in Fig. 8 where the projections 36 abut to enclose the tongue 26 in a rectangular slot. The pivot 15 which secures the fixed jaw to the handle passes through the projections 36 and thus holds the wings 35 in position and a welding operation for these parts is not necessary.
- 15 20 Having thus described my invention, I claim:

An adjustable wrench as described comprising a handle, a fixed jaw and a sliding jaw, said fixed jaw connected by a pivot to said handle and having a rectangular slot, 25 also an arcuate slot formed about a radial centre at right angles to said rectangular slot, said pivot passing through the radial centre of said arcuate slot and forming a ridge transverse to and on the lower side of said 30 rectangular slot and said sliding jaw having a tongue fitting said rectangular slot with its lower side under-cut to clear said pivot and permit a limited sliding movement of said jaw, there being a slot in said tongue transverse to its plane of movement aligning with said arcuate slot and a pin passing through said handle, arcuate slot and transverse slot whereby said sliding jaw is actuated relative 35 to said fixed jaw by said handle. 40

In testimony whereof I affix my signature.

ABRAHAM S. PINKUS.
